UNITED STATES PATENT OFFICE

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK

DYEING APPARATUS

Application filed October 1, 1930. Serial No. 485,616.

This invention relates to dyeing apparatus, and more particularly to apparatus for the partial or multi-color dyeing of wound masses of yarn.

5 A particular object of the invention is to provide for applying the so-called Eclipse-Van Ness hydraulic method of dyeing described in Van Ness U. S. Patent No. 1,456,344 to the partial or multi-color dyeing of packages of rayon yarn. It has been found that the particular injecting apparatus described in said Van Ness U. S. Patent No. 1,456,344 and in the later Van Ness Patents, Nos. 1,577,884 and 1,606,196, while highly satisfactory in the dyeing of other kinds of yarn, is not applicable to the dyeing of rayon yarn because the construction of the rayon threads on dyeing makes it difficult to remove the needles without cutting the thread. This difficulty is overcome by the present invention which provides for the use of injectors without needles in such a way as to obtain even dyeing of particular portions of the yarn mass. A further feature of the 25 invention provides for making a sharp line of demarcation in multi-color dyeing.

While the invention is of especial value in making the Van Ness method of dyeing applicable to rayon, the use of the new machine is by no means limited to dyeing rayon, as it may be applied to all other kinds of yarn.

The invention will be further explained in connection with a detailed description of a practical dyeing machine embodying the 35 invention and illustrated in the accompanying drawings, in which:

Fig. 1 is a plan view with the base plate partly broken away, showing the yarn mass spaced from the injectors;

40 Fig. 2 is an enlarged longitudinal section taken on the line 2-2 of Fig. 1, and showing the yarn mass in position for dyeing;

Fig. 3 is a partial transverse section taken on the line 3-3 of Fig. 1, showing the pump;

45 Fig. 4 is an enlarged horizontal section taken on the plane of the axes of the dye nozzles, which is indicated by the line 4-4 in Fig. 5; and

50 Fig. 5 is a front elevation of the presser and injector nozzles.

The machine illustrated in the drawings is a multi-color dyeing machine similar in general construction to that shown in my Patent No. 1,726,984. It includes a base plate B carrying a multi-cylinder pump P and a workholder W. In the operation of the machine, the pump draws different colored dyes from a plurality of separates reservoirs Ta, Tb, Tc and Td, and forces limited quantities of the different colored dyes into separate portions of a mass of yarn on the workholder W through a plurality of nozzles J in a presser A whose construction constitutes a particular feature of the invention.

The means for operating the pump and for supporting, translating and rotating the spindle of the workholder are identical with those described in my Patent No. 1,726,984, to which reference is made for a detailed description of these parts which may be readily applied to the drawings of the present application, since the reference numerals used in said patent have been applied to the identical or corresponding parts shown in the drawings of the present application. It should be noted, however, that in the present instance the pump cylinders P6a, P6b, P6c and P6d are all rigidly attached to the slide P13 so that their strokes are simultaneous and equal, and that the shaft W3 of the workholder W is provided with a cylindrical extension W4 adapted to fit the bore of a cylindrical bobbin or core C1.

The portions of the machine illustrated which cooperate directly with the yarn differ from those shown in my patent above referred to. The yarn mass C consists of a thin, hollow, cylindrical layer wound on a cylindrical core C1 whose radius is several times as great as the depth of the yarn mass. The separate injectors of my machine shown in Patent No. 1,726,984 are replaced by a presser A, which is secured to the cylinder block P1 of the pump P over the outlet openings P24 of the pump cylinders. The outer vertical surface A1 of the presser is concave and cylindrically curved, having substantially the same radius as the outer surface of the yarn mass C, so that it is adapted to fit evenly against a portion of the circum-

- ferential surface of a yarn mass from one end of the mass to the other. The presser contains a plurality of holes or bores A2 extending through its surface A1 and connected 5 in groups by passages A3 with the outlet openings P24 of the pump cylinders. In the outer end of each bore A2 is seated a nozzle A4 which most desirably projects from the surface A1 of the presser.
- 10 It will readily be understood that, when the workholder W is operated to move the yarn mass toward the pump into the position shown in Fig. 2, the surface A1 of the presser A fits against the circumferential surface of 15 the yarn mass C and evenly compresses an extended portion of this surface. While the machine operates very satisfactorily with a portion of the yarn thus evenly compressed, an advantage is gained by providing for an 20 additional compression of narrow intermediate zones of the compressed portion which separate the parts of this portion into which different colored dyes are injected. In the machine illustrated, such additional compression 25 is secured by providing the pressing surface A1 of the presser A with projecting transverse ridges A5, which are located between the sets of nozzles A4 communicating with the different pump cylinders.
- 30 The use of the machine from the operator's point of view is the same as that described in my Patent No. 1,726,984. The workholder is reciprocated towards and away from the pump. At the end of each inward stroke, a 35 portion of the yarn is evenly compressed by the surface A1 of the presser A, and the pump then makes one compression stroke which forces the dyes of different colors under equal pressures into different parts of this evenly 40 compressed portion of the mass. The shaft of the workholder is rotated slightly after each outward stroke, so that successive sectors of the mass are dyed in four colors until at the end of the operation there are four bands 45 of different colors extending around the mass. The pressure exerted by the pump pistons is sufficient to cause the dye injecting from each nozzle to penetrate through the shallow mass from its outer to its inner surface in 50 the absence of any mechanically opened passage for the injected dye. This, combined with the even pressure on the portion of the mass being dyed, results in a very even spreading of the dye. By proper adjustment of the 55 length of the stroke of each pump piston, the quantity of dye inserted through each set of nozzles at each injection is just sufficient to dye the portions of the compressed part of the mass between the ridges A5. The result 60 is a very even and sharp line of demarcation between the different colored bands in the mass, avoiding any undyed portions between the bands and any substantial overlapping or mixing of the colors. The dyeing

in each band is uniform from the outer surface to the inner surface of the mass.

What I claim is:

1. Apparatus for dyeing a wound mass of 70 yarn, comprising a presser having an extended concave surface formed to fit against a circumferential surface of the mass of yarn so as evenly to compress a portion of the mass, and means for injecting dye through the presser into a portion of the yarn compressed by said surface.
2. Apparatus for dyeing a wound mass of 75 yarn, comprising a presser having an extended concave surface adapted to fit against a surface of the mass so as evenly to compress a portion of the mass, a plurality of nozzles projecting from said surface of the presser, and means for injecting dye through said nozzles simultaneously into a portion of the mass compressed by the presser.
3. Apparatus for multi-color dyeing of a 80 wound mass of yarn, comprising a presser having an extended concave surface adapted to fit against a surface of the mass of yarn so as evenly to compress a portion of the mass, said presser containing a plurality of spaced holes extending through its said surface, and means for simultaneously injecting, under the same pressure, dyes of different colors 85 through said holes.
4. The method of multi-color dyeing a wound mass of yarn, which comprises evenly compressing an extended portion of the mass of yarn and additionally compressing intermediate zones of said portion, and injecting different colored dyes into the different parts of said compressed portion separated by said zones.
5. Apparatus for multi-color dyeing a 90 wound mass of yarn, comprising a presser having an extended surface adapted to fit against a surface of the mass of yarn so as evenly to compress a portion of the mass, spaced transverse ribs on said surface of the presser adapted to apply additional pressure to spaced zones of said portion of the mass, and means for simultaneously injecting dyes of different colors through said presser between said ribs.
6. The method of dyeing yarn, which comprises forming the yarn into a thin hollow cylinder having a thickness materially less than its internal radius, evenly compressing a portion of said cylinder and injecting a limited quantity of dye radially into said portion of the cylinder under a pressure sufficient to cause it to permeate throughout the compressed portion in the absence of a mechanically opened passage.

In testimony whereof I have hereunto set my hand.

LOUIS B. HASBROUCK.
